US0D1094032S

(12) **United States Design Patent** (10) **Patent No.:** **US D1,094,032 S**
(45) **Date of Patent:** **** Sep. 23, 2025**

(54) **SCOOP**

(71) Applicant: **Shenzhen Tieweilntelligent Technology Co., LTD**, Shenzhen (CN)

(72) Inventor: **Yujun Zhou**, Shenzhen (CN)

(73) Assignee: **Shenzhen Tieweilntelligent Technology Co., LTD**, Shenzhen (CN)

(**) Term: **15 Years**

(21) Appl. No.: **29/933,634**

(22) Filed: **Mar. 20, 2024**

(30) **Foreign Application Priority Data**

Sep. 22, 2023 (CN) 202330620433.7

(51) **LOC (15) Cl.** **07-99**

(52) **U.S. Cl.**

USPC **D7/681**

(58) **Field of Classification Search**

(57) **CLAIM**

The ornamental design for a scoop, as shown and described.

DESCRIPTION

FIG. 1 is a front, right and bottom perspective view of a scoop showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the scoop that form no part of the claimed design.

1 Claim, 8 Drawing Sheets
